UNITED STATES PATENT OFFICE.

ALBERT O. TROSTEL, OF MILWAUKEE, WISCONSIN.

ARTICLE OF MANUFACTURE AND METHOD OF PRODUCING THE SAME.

1,250,051.

Specification of Letters Patent.

Patented Dec. 11, 1917.

Application filed September 27, 1916. Serial No. 122,360.

To all whom it may concern:

Be it known that I, ALBERT O. TROSTEL, a citizen of the United States, residing at Milwaukee, Milwaukee county, Wisconsin, have 5 invented a certain new Article of Manufacture and Method of Producing the Same, of which the following is a specification, reference being had to the accompanying drawings, forming a part thereof.

10 My invention relates particularly to a new kind of pattern-surfaced leather that is to be used for ornamental purposes, such as shoes, belts, pocket-books, and a variety of other uses wherein a handsome appearance 15 of the leather is important. The main object of my invention is to give a finish to the leather, which incorporates a pattern, that I may vary at will, and at the same time have the leather retain its original flat- 20 ness and substantially all of the original grain. I am fully aware that patterns have been produced upon leather by stamping or embossing thereon, so as to produce a raised pattern, but I know of no one who has suc- 25 ceeded in producing a pattern upon leather which retains its original texture, flatness, and substantially all of its original grain and does not have the appearance of having been artificially pressed or roughened. The 30 difficulty with leather that has been em- bossed is that owing to its unevenness the high spots easily scuff off and the leather will not retain its shape but will stretch and stretch unevenly and is unusable for many 35 purposes. I obviate both of these defects by my process.

In the drawings Figure 1 shows a design that I have applied to leather consisting of irregularly shaped, mottled light and dark 40 spots; Fig. 2 shows a piece of leather embodying my invention and having a pattern like that of watered silk; Fig. 3 shows a piece of leather having a geometrical design of a star thereon. The surface of each 45 of these is flat, the design not being in any way raised or embossed.

To make my new style of leather, I first press the grain side of the leather into intimate contact with a die or plate having the 50 pattern I desire to impress upon the leather, slightly raised or embossed thereon. This embossing is but a temporary embossing and I sometimes call it "fugitive embossing," because the embossing *per se* disappears and 55 does not remain in the final result. I then submit the grained surface of the leather to

the action of a buffing wheel, regulating the amount of buffing dependent upon the amount of grain I wish to remove and the difference in color or sheen that I wish to develop. The portions of the surface of the leather that have been raised by the action of the die or plate are subjected to more abrading action of the buffing wheel, with the result that more of the grain, and consequently more of the color and texture are removed therefrom than from the portions of the leather which are not so raised. I find that by having the pattern on the die or plate consist of relatively small subdivided areas better results are produced, as I am thus able to better control the differential action of the buffing wheel. This does not mean that the pattern itself must necessarily be small, or cover the entire surface 75 of the leather, but that it shall be composed or made up of relatively small contrasting parts or areas. By making the pattern on the die or plate very shallow I am enabled to raise the corresponding surfaces of the 80 leather a minimum, but nevertheless sufficient amount to permit of the differential action of the buffing wheel upon the raised surface and the intaglio surface of the leather, which results in the leather's being 85 substantially flat after the buffing is completed. As a result of this, I obviate high spots which are subjected to scuffing, nor do I get a leather which will stretch and lose its shape. 90

By the expression "substantially flat" as used herein and in the claims I do not mean that every vestige of the embossing must be eliminated or that the leather must be a plane and not a curved surface, but rather 95 that the relief shall be practically eliminated.

If preferred, or if more pronounced differences in color or texture are desired than can be obtained by merely slightly impressing the pattern upon the leather, I make the die or plate with a slightly deeper impression and in this event do not buff the leather clear down to a flat surface. If I operate in this latter manner, I preferably there- 100 after subject the leather to heavy pressure between flat plates to again reduce it to the shape of its original flatness. The finish is then put upon the leather in the ordinary way. As a result of this process I get a pattern upon the surface of the leather while 105 the leather itself is flat and will retain its 110

original shape and strength, not being subject to stretching, nor is the pattern subject to scuffing off because of the inequalities thereof.

5 I can also emphasize the pattern and produce some very striking effects by dyeing my leather with a basal color which is different from the surface color. Thus, I may dye the leather with a basal color of blue 10 and a surface color of brown. As a result thereof when the leather is treated by my process the high lights of the pattern are shown up in blue against a background of brown. Even though this is not done there 15 is quite a remarkable difference in color. Thus, the portions that are buffed in black leather show blue. In the case of white leather, while the color is the same, the sheen is different. In brown leather the high spots 20 show brown but the tone thereof is different. I am thus enabled to vary not only the sheen and tone but also the color and am enabled to have a pattern of say a green tree or star 25 against a brown background. In this way I am also enabled to identify my leather by marking my name thereon, preferably in the same color and very lightly, it appearing in the finished product much as a watermark appears upon paper.

30 While I generally employ my process upon the grain side of leather, I do not limit myself thereto as it may be applied to the flesh side thereof or to a split.

Having thus described my invention, I 35 claim:

1. A process of finishing leather, which consists in producing a temporary, low-re-

lief pattern of relatively small subdivided areas upon its surface, and then dressing off the surface of the temporary relief portions 40 and restoring the leather to substantial flatness.

2. A process of finishing leather, which consists in producing a temporary, low-relief pattern of finely subdivided areas upon 45 its surface, dressing off the surface of the temporary relief portions, thereby producing contrast between the temporary relief and intaglio parts of said pattern, and restoring the leather to substantial flatness. 50

3. A process of finishing leather, having a surface finish of a color different from that of its sub-surface which consists in producing a temporary low-relief pattern of finely subdivided areas upon its surface, then removing so much of the surface of the temporary relief portions as to expose the sub-surface coloring, thereby producing contrast 55 between the temporary relief and intaglio parts of said pattern and restoring the 60 leather to substantial flatness.

4. As a new article of manufacture, pattern-surfaced leather, having a surface that is substantially flat and smooth, and is provided with an integrally-incorporated pattern consisting of relatively small subdivided, differentiated areas, produced by differential buffing. 65

In testimony whereof I hereunto affix my signature in the presence of two witnesses. 70

ALBERT O. TROSTEL.
